UNITED STATES PATENT OFFICE.

MICHAEL SCHOEN, OF NEW YORK, N. Y.

DESIGN FOR A DOLL.

59,289.

Specification for Design.

Patented Oct. 4, 1921.

Application filed April 16, 1921. Serial No. 462,038. Term of patent 7 years.

To all whom it may concern:

Be it known that I, MICHAEL SCHOEN, a citizen of the United States, residing in New York, in the county of New York and State of New York, have invented a new, original, and ornamental Design for a Doll, of which the following is a specification, reference being had to the accompanying drawing, forming part thereof, which is a perspective view of the same.

I claim:—

The ornamental design for a doll as shown.

MICHAEL SCHOEN.
